UNITED STATES PATENT OFFICE.

JOHN McCREARY, OF COHOES, AND DAVID R. SMITH, OF TROY, ASSIGNEES
OF ONE-HALF TO GEORGE H. BILLINGS AND EZRA W. CARTER, BOTH OF
COHOES, NEW YORK.

MACHINE FOR RADIAL CRIMPING.

SPECIFICATION forming part of Letters Patent No. 284,749, dated September 11, 1883.

Application filed December 26, 1882. (No model.)

To all whom it may concern:

Be it known that we, JOHN McCREARY, of Cohoes, county of Albany, State of New York, and DAVID R. SMITH, of Troy, county of Rensselaer, State of New York, have invented new and useful Improvements in Methods of and Machines for Radial Crimping, of which the following is a full, clear, and exact description, reference being had to the accompanying drawings, making part of this specification.

Our invention relates to that method of radial crimping in which radial or diverging or converging crimps, folds, or fold-marks suitable for filtering-paper are produced in filtering-paper or other material by compressing the paper or material on the lines of the several folds between suitable and suitably-arranged radial or diverging or converging grooves and edges. When all the folds, fold-marks, or crimps required in a sheet of filtering-paper are made by the simultaneous action of a sufficient number of suitable grooves and edges, the several edges pressing against opposite faces of the intervening paper cause friction and produce a strain, which is liable to tear the paper while it is being drawn in between the said grooves and edges by the simultaneous closing of the same grooves and edges upon the said intervening paper.

The object of our invention is to provide improved means for radially crimping filtering-paper or similar material, and adapted to form the radial crimps or fold-marks one after another or successively, instead of simultaneously, in such manner as to avoid the liability of tearing or otherwise injuring the material operated upon; and to this end the invention consists in the combination, in a machine for producing radial crimps, folds, or fold-marks, of a stationary bed-plate provided with radial grooves and edges, a series of converging blades operating in connection with said grooved bed-plate, and means for actuating said blades successively, or one after another, as hereinafter described.

In the accompanying drawings, Figure 1 is a side elevation, and Fig. 2 a plan, of a machine for radial crimping embodying our invention, and suitable for manufacturing radi-

ally crimped or folded filtering-paper. Fig. 3 is a side elevation, part section, of a slotted cam-rod, showing friction-roller in section, friction-roller stud, and a cam, showing also the relative position of the parts. Fig. 4 is a plan of fulcrum-shaft. Fig. 5 is a top view of transverse guide-bar. Fig. 6 is a plan of cam-shaft with the several cams fixed thereon. Fig. 7 is an end view of the same, showing also a side elevation of one cam-rod in a position corresponding to the position of the shaft and cams. Fig. 8 is a diagram serving to facilitate the explanation of details.

In all the figures like parts are indicated by the same letters of reference.

A and B are suitable edge and groove carriers or holders, so arranged, guided, and operated that the several grooves and edges are opened and closed in the manner required for the purposes of our invention. The several carriers or holders B, grooves a, edges b, cams d, rods C, rollers e, bearings k, washers j, and studs m are numbered as seen in the drawings, for convenience of reference.

All the grooves a and edges b which act on or receive one side of the paper are fixed to and carried by one and the same carrier, A. In the example shown in the drawings the carrier A is fixed, and is firmly supported by a suitable frame, F. The several grooves a and edges b acting on the opposite face of the paper are carried by movable holders B, in the present example twelve in number. The several movable holders B are so operated that the same grooves a and edges b carried by them are caused to act one after another upon the paper in such manner that edge b' of carrier B', for example, on the line of the first fold forces the paper into the opposite groove, a', of the carrier A, and holds it there until the next or adjacent holder, B², has carried edge b² into the opposite groove, a², &c., the several holders or carriers B acting in a similar manner successively until the last fold is made. The grooves a and edges b, carried by holder or carrier A, all radiate from a common center, o, corresponding to the center of the sheet of filtering-paper to be folded or crimped. The grooves a and edges b car-

ried by carriers or holders B correspond in form with those on carrier A, and when compressing the paper all radiate from the same point, *p*, separated from point *o* only by the 5 thickness of the intervening paper. In the drawings the several carriers B are levers, parallel for a part of their length with each other and with the central groove, *a*¹², and edge *b*¹², and are hinged to A by a fulcrum 10 bolt or shaft, I, and boxes J, boxes J being rigidly attached to lugs H, projecting from the said carrier A.

D is a hand-wheel secured to one extremity of a cam-shaft, G, which shaft is carried by 15 bearing-boxes *f*, one of which boxes is shown in dotted lines in Fig. 1. Boxes *f* are supported by arms or brackets *g*, projecting from frame F.

The slotted cam-rod C, connected severally 20 at their upper extremities to the several carrier-levers B, are properly guided longitudinally by the holes or bearings *k* in the transverse guide-bar K, and are prevented from turning partially by the joint or connection 25 with the carriers B and partially by the side faces of the several cams *d*. The middle part of the several cam-rod C is widened and slotted to span the hubs of the several cams *d*.

Twelve cams, *d*, differing from each other 30 only in the length of the hub, are firmly secured to the cam-shaft G, and, acting severally on the several friction-rollers, *e*, communicate end-long motion to the several corresponding cam-rod C, to which the rollers *e* are attached.

35 The friction-rollers are held against the faces of the cams, and the return motion is secured by the action of spiral springs E, confined between washers *j* on the cam-rod and the under side of the transverse guide-bar K. The 40 transverse guide-bar K is secured to the frame by screws or screw-bolts passing through holes *l* of the bar K and into or through projections *h* of the frame.

Suitable studs, *m*, projecting from the faces 45 of cam-rod C, carry the friction-rollers *e*. The hubs *n* of cams *d* pass through the slots of rods C, allowing the side faces of the cams to approach the rods, as shown in Fig. 3.

e is an adjustable guide and gage consisting of a straight edge or face projecting upward from the face of the carrier or holder A. The center of guide *e* should coincide with the center *o*. The gage and guide *e* is rendered adjustable by slots in the lugs *q*, by which it 55 is secured to carrier A, for the purpose of so regulating the space *r* between the guide and the first groove that the first and last folds of the filtering-paper may be of equal width.

In the drawings the machine is represented 60 in position to receive the paper or material to be operated on. The sheets of filtering-paper are to be first folded through the center on one diagonal, if the sheets are square, or on one diameter, if the sheets are circular. If the 65 operator, placing himself in front of the machine at X, places one of the thus-folded sheets of filtering-paper upon carrier A, with the

fold against the guide *e*, the center of the paper coinciding with center *o*, and with the paper thus placed in position communicates motion with his right hand to the rim of wheel D in the direction of the arrow, the cam *d*, acting on roller *e*, will force up the rod C, and with it the short arm of the carrier-lever B, the long arm of which lever carrying edge *b*¹² will force that edge down on the paper and force the paper down into the corresponding groove, *a*¹², compressing it then and forming the first crimp-fold or fold-mark required. 70

The form of cams *d* and their relative positions on shaft G are such that, the shaft G continuing to move in the same direction, the edge *b*¹² will reach its lowest position before *b*³ does, and will remain in that lowest position, holding the paper until *b*³ has also reached its 85 lowest position, forming the corresponding crimp, fold, or fold-mark; and so likewise of the succeeding folds, the carriers B' B² B³, &c., coming down one after the other in the order of the numbers, each edge and groove holding 90 the paper until the next succeeding fold or crimp is made. About two-thirds of one revolution of shaft G being sufficient to produce all the folds required, one complete revolution of shaft G completely crimps a sheet of filtering-paper and returns the several moving parts of the machine to the position shown in the drawings, ready to receive a second sheet of paper and repeat the operation. 95

Let Fig. 8 represent a possible section of the three carriers or holders B' B² B³ and a portion of the edge of carrier A. It will be seen that the grooves *a*², *a*⁴, and *a*⁶ are formed by bringing the several carriers into the relative positions shown in the figure, B², for example, carrying the edge *b*³ and one side each of grooves *a*² and *a*⁴; but, if preferred, for convenience or facility of construction, the several carriers B may be made to carry any convenient parts or portions of the several grooves 105 and edges.

It is evident that if the guide *e* should be removed from the fixed carrier A one half of a sheet of filtering-paper could be crimped by the machine without previously folding the paper through the middle or center, and that having thus folded, marked, or crimped one half, the other half could be folded or crimped in the same manner. Therefore we do not confine ourselves to the crimping of 110 sheets of filtering-paper previously folded through the center; but,

Having thus described our invention, what we claim as new, and desire to secure by Letters Patent, is—

1. In a machine for producing radial crimps or fold-marks, a stationary bed-plate or holder provided with grooves and edges radiating from a common center, in combination with a series of converging blades, and means, 120 substantially as described, for actuating said blades successively, or one after another.

2. In a machine for producing radial crimping, a stationary bed-plate provided with

grooves and edges radiating from a common center, in combination with a series of converging blades united to parallel arms or holders pivoted all in the same axial line, 5 and operating substantially as described.

3. In a machine for producing radial crimps or fold-marks, a stationary bed-plate provided with grooves and edges radiating from a common center, in combination with a series of 10 independently-actuated pivoted blades, also converging to a common center, and means, substantially as described, for connecting said blades with and actuating them from one and the same shaft, substantially as described.

15 4. In a machine for producing radial crimping, the fixed bed-plate or holder A, pro-

vided with the radial grooves *a* and edges *b*, in combination with the parallel and independently-acting movable holders B, pivoted to the holder A, and provided with the converging blades or edges *b'*, and suitable rods connecting said holders with and adapting them to be operated all from one and the same cam-shaft, substantially as described. 20

In testimony whereof we have hereunto set 25 our hands this 14th day of December, A. D. 1882.

JOHN McCREARY.
